P. A. Palmer of Le Roy N.Y.
Letters Patent No. 281. Dated April 30, 1850.

The Schedule referred to in these Letters Patent and making part of the same.

To all to whom these presents shall come:

Be it known that I, P. A. Palmer, of Le Roy, in the County of Genesee, and State of New York, have invented or produced a new design of Cook Stove which I call the Genesee valley air tight, and I do hereby declare that the following is a full, clear, and exact description of the same, reference being had to the annexed drawings making a part of this specification, in which fig. 1, is an isometrical perspective view of the Stove, fig. 2 and 3 a view of the end door representing the ornaments thereon, and fig. 4, a view of the oven door.

There are two doors in front, which are not represented in the drawing, they being the same in the mouldings and ornament, as the end door B, represented in fig. 2.

Having thus described the nature of my new design, what I claim therein as new and desire to secure by Letters Patent is the design of ornament and configuration, constituting in combination a new design of Stove, substantially the same as herein described and represented in the annexed drawings.
